UNITED STATES PATENT OFFICE.

MILLARD VAN BLARICOM, OF NEW YORK, N. Y.

DESIGN FOR COMBINED LOUD SPEAKER AND LAMP.

Application filed December 9, 1925. Serial No. 15,699. Term of patent 3½ years.

To all whom it may concern:

Be it known that I, MILLARD VAN BLARICOM, a citizen of the United States, and resident of the city of New York, county of New York, and State of New York, have invented a new, original, and ornamental Design for Combined Loud Speaker and Lamp, of which the following is a specification, reference being had to the accompanying

drawing, which forms part of the same, and in which—

Fig. 1 shows a view in elevation of a combined loud speaker and lamp constructed in accordance with the present design.

I claim:

The ornamental design for combined loud speaker and lamp substantially as shown.

MILLARD VAN BLARICOM.
